(57) **CLAIM**

We claim the ornamental design for a cosmetic container, as shown and described.

DESCRIPTION

FIG. 1 is a perspective view of a cosmetic container, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a sectional view thereof taken along line 8-8 in FIG. 2; and,

FIG. 9 is an exploded perspective view thereof.

(Continued)

The broken lines in the drawings illustrate portions of the cosmetic container which form no part of the claimed design.

1 Claim, 5 Drawing Sheets
